UNITED STATES PATENT OFFICE.

MATTHEW GRISWOLD, JR., OF ERIE, PENNSYLVANIA.

GAS HEATING-STOVE.

SPECIFICATION forming part of Letters Patent No. 650,603, dated May 29, 1900.

Application filed December 21, 1899. Serial No. 741,126. (No model.)

To all whom it may concern:

Be it known that I, MATTHEW GRISWOLD, Jr., a citizen of the United States, residing at Erie, in the county of Erie and State of Pennsylvania, have invented certain new and useful Improvements in Gas Heating-Stoves; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 This invention relates to improvements in gas heating-stoves; and it consists, substantially, in the features thereof hereinafter set forth, described, and claimed, and illustrated in the accompanying drawings, in which—

20 Figure 1 is a vertical section of my improved gas heating-stove on the line $x-x$ in Figs. 2 and 4. Fig. 2 is a vertical section of the same on the line $y-y$ in Fig. 1. Fig. 3 is a top or plan view of the same. Fig. 4 is a 25 transverse section of the lower part thereof on the line $z-z$ in Fig. 1.

The stove thus illustrated is designed particularly for burning gas fuel and is provided with both air-flues and flues for carrying off 30 the products of combustion. Many of the stoves designed for burning gas fuel have no provision for carrying off the products of combustion, and others so provided apply the heat of the gas fuel burned to the air-flues 35 unevenly, so that the best results are not realized therefrom. Again, in the better types of stoves of this character the ends and back of the stove form portions of the air-flues and cannot therefore be removed and replaced 40 with new ones when cracked or burned out without practically rebuilding the entire stove. To overcome these difficulties, I have so constructed the stove and located the air-flues therein that not only is there a comparatively even distribution of the heat generated 45 to all of the air passing through them, but the entire system of flue and burner mechanism can be removed from the stove-body and the whole or parts thereof be replaced with new portions without replacing 50 any portion of the outside of the stove, thus

making the repair thereof a comparatively simple matter.

In the drawings, A is the base of the stove; B, the front, B' the ends, and C the back, 55 thereof, these parts comprising the stove-body. In the lower part of the stove-body there is a gas-burner, made in two sections D and D', the base A being provided with openings a to supply air thereto. In the back of 60 the stove-body there is a vertical chamber E, which is substantially the same width and height as the stove-body. The bottom of this chamber E is open, and through the base A there is an opening a' equal in area with the 65 open bottom of the chamber E, so that air can pass upward therethrough.

From the top of the chamber E a horizontal chamber F extends forward to the front of the stove, and in this chamber F there is a 70 baffle-plate f , which extends from the rear of the chamber forward nearly to the front thereof, so that air passing up through the chamber E must pass under the baffle-plate f entirely over the plate f' before it escapes past 75 the front edge of the baffle-plate f , and as the plate e , forming the inside wall of the chamber E, and the plate f' , forming the lower wall of the chamber F, form the back and top of the fuel combustion-chamber of the stove 80 it is obvious that the air in passing over the plates will become thoroughly heated before being discharged into the flues above, as hereinafter described. In addition to the air-inlet chamber E, I place two pipes or flues G and G' in 85 the combustion-chamber, each of which passes down through openings between the portions D D' of the gas-burner and through the base A, while the upper ends thereof extend through the plate f' of the chamber F, so that 90 air will pass up freely therethrough into the chamber F below the baffle-plate f . In this manner a large amount of air passes up through and adjacent to the combustion-chamber to be heated thereby.

95 The front B and the ends B' of the stove-body I have shown as curved plates, with the gas-burner surrounded at the front and ends by a grating H, adapted to retain clinkers or other non-combustible material placed upon 100 the burners from contact with the front and ends of the stove-body, thus permitting me

to construct both the front and ends of the stove-body with illuminated mica-filled openings.

In the top of the stove-body I place flues $I I'$ 5 at the sides, which at their lower ends open into the ends of the combustion-chamber around and over the ends of the chamber F , as illustrated by the arrows $i i'$, their upper ends opening into a hollow chamber J , which 10 is provided at its rear with a stovepipe-thimble j in the usual manner, to which ordinary stovepipe may be attached. Between the flues $I I'$ are also vertical flues $K K' K''$, the lower ends of which open into the chamber F 15 above the baffle-plate f therein, while the upper ends of these flues extend up through the top of the hollow chamber J , so as to discharge the heated air passing up therethrough out into the room. It will be observed that 20 the construction and arrangement of the heating-chambers E and F and the heating-flues $G G'$, with relation to the base, front, ends, and back of the stove-body, is such that they or any part of them can be taken out and replaced without having to replace any portion 25 of the stove-body, and as these parts are liable to be burned out frequently in stoves of this type this feature of the construction is an important one.

30 Having thus described my invention, so as to enable others to construct and use the same, what I claim as new, and desire to secure by Letters Patent of the United States, is—

1. In a gas heating-stove, the combination 35 of a vertical shell comprising the walls of a vertical draft-chamber and the back of a combustion-chamber, independent of and separated from the back wall of the stove-body, and a shell comprising the walls of a horizontal chamber, communicating at its rear with the top of said vertical chamber and forming the top of a combustion-chamber, and a baffle-plate extending from the rear nearly to the front of said horizontal chamber, substan- 40 tially as set forth.

45 2. In a gas heating-stove, the combination of a stove-body, a gas-burner in the lower por-

tion thereof, a vertical shell independent of the walls of the stove-body, forming the back of the combustion-chamber and opening 50 through the stove-body base, a horizontal shell forming the walls of a chamber over the top of the combustion-chamber and communicating at its rear with the top of said vertical shell, and pipes forming flues extending 55 from openings in the stove-base up through the combustion-chamber and into the bottom of said horizontal shell, substantially as set forth.

3. In a gas heating-stove, the combination 60 of a stove-body inclosing a combustion-chamber, shells, the walls of which form vertical air-flues, extending up through the combustion-chamber, and a vertical plate forming the rear wall of the combustion-chamber, and 65 the inner wall of a vertical air-flue, a horizontal shell communicating with said vertical air-flues and with said vertical back flue, forming the top of said combustion-chamber, and a baffle-plate in said horizontal shell, di- 70 viding it horizontally, substantially as set forth.

4. In a gas heating-stove, the combination 75 of a stove-body inclosing the sides and the bottom of a combustion-chamber, a shell forming the back of said combustion-chamber and forming an air-flue, shells extending up through the said combustion-chamber and forming air-flues, a horizontal shell communicating with said air-flues and forming the 80 top of said combustion-chamber, pipes forming flues for the products of combustion extending from the top of the ends of said combustion-chamber upward into a hollow shell on the top of said flues, and shells forming 85 air-flues extending up from the horizontal shell forming the top of the combustion-chamber, substantially as set forth.

In testimony whereof I affix my signature in presence of two witnesses.

MATTHEW GRISWOLD, JR.
